UNITED STATES PATENT OFFICE

ARTHUR J. HARTLEY, OF PEORIA, ILLINOIS

GRAIN-CLEANING DEVICE

Application filed September 30, 1929. Serial No. 396,068.

This invention relates to grain cleaning devices.

One of the objects of the invention is in the provision of a grain cleaning device comprising a perforated cylinder, there being disposed therein a rotatable member having a plurality of blades thereon adapted to agitate the grain during its continuous course through the cleaner in a manner to expel the weed seeds and other extraneous matter from the grain.

Another object lies in the provision of a grain cleaning device comprising an apertured cylinder, there being mounted within the cylinder a rotatable member having a plurality of blades therein operated to agitate the grain and clean same, there being also connected to this rotatable member an auger portion operating to deflect the incoming grain directly upon the agitating blades.

Still another object lies in the provision of a grain cleaning device comprising an apertured cylinder, the same having cooperatively related thereto and operating therein, means for deflecting the incoming grain into a series of blade members which operate to agitate the grain with the result of expelling the weed seeds and other extraneous matter from the grain, there being also provided within the cylinder a series of scoop members which operate to eject the cleaned grain from the device.

Other objects will appear in the following specification, taken in connection with the annexed drawings, in which—

Fig. 1 is a plan view of my grain cleaning device;

Fig. 2 is a front elevation of the device, a portion thereof being broken away for a more detailed view of various parts;

Fig. 3 is an end elevation;

Fig. 4 is an end elevation from the opposite side to that shown in Fig. 3;

Fig. 5 is a cross-sectional view taken on the line 5—5 of Fig. 6;

Fig. 6 is a sectional view taken on the line 6—6 of Fig. 5; and

Fig. 7 is a sectional view of one of the cleaning blades.

50 The present grain cleaning device is

adapted to be used on the well known combine which in its uneven travel through the field accomplishes a plurality of grain handling operations simultaneously with a single machine rather than by interrupted and intermittent operation of a number of machines.

Looking to the end of accomplishing the result of evenly cleaning the grain during the movement of the combine through the field, applicant has devised a grain cleaner so fashioned as to operate efficiently irrespective of this uneven travel of the beforementioned combine.

Now, referring to the drawings, there is shown the following structure: 10 refers to a sheet metal housing or cover for the grain cleaner which has the end plates 11 and 12. A grain funnel or receiving portion 13 is disposed at one side of the grain cleaner and in such position that the grain is delivered to the cleaner from an elevated position and falls by gravity directly into the cleaner.

Within the cleaner and perhaps best shown in Fig. 6 of the drawings, is a shaft 14 having suitable bearings 15 and 16 respectively in the previously described end plates 11 and 12. Upon the shaft 14 and at a point immediately below the grain receiving funnel 13 is mounted an auger member 17, or rather a portion of an auger member. This member 17 is so fashioned and arranged that it not only receives the threshed grain but deflects and propels the same towards the rotatable agitating and cleaning member, generally referred to as 18, and directly into the path of the latter. This rotatable grain cleaning member comprises a frame portion 19 which is secured to the shaft 14 in the manner shown in Fig. 5. Radiating from this frame portion 19 are a series of blade members 20 disposed in a spaced relationship within the surrounding cylindrical screen 21. A portion of this screen is shown in Fig. 2 of the drawings and may be described as a cylindrical apertured portion, said apertures being of such size as to prevent the exodus of the grain but permitting the separation of the weed seeds and extraneous matter from the grain, and the passage of same there-

through. This screen has its ends suitably secured to the previously described end plates 11 and 12.

Beneath the screen 21 is a hopper 22 in which rotates an auger 23. This auger is disposed in the bottom of the hopper and in such position as to pick up the separated weed seeds and other matter and to force same out of the cleaner into any receptacle that may be utilized to receive same. This auger 23 is mounted upon a shaft 24 which has suitable bearing supports in the end plates 11 and 12 of the cleaner.

With respect to the series of grain agitating and cleaning blades 20, it might be stated that in each of the series there is a plurality of angularly positioned blade members, one of said blades being shown in Fig. 7 of the drawings. These blades are so fashioned and arranged as not only to agitate the grain delivered thereto by the auger 17 over the surface of the screen, but also to move the grain towards the opposite end of the cleaner and finally to such a point that same is picked up by the plural scoops 25. These scoops are secured, as at 26, to a plate 27 which in turn is fixedly attached to the shaft 14 and rotates therewith.

As respects the operation of applicant's grain cleaning device, the grain is delivered by gravity or any desirable means, directly into the cleaning device, whereupon the auger, or rather the auger portion, deflects the incoming grain directly into the path of the rotating blades, which in turn agitate the grain over the inner surface of the perforated cylinder. These blades also operate to move the grain continuously through the cleaner. The agitation of the grain against the cylinder results in the explosion of the weed seeds and other extraneous matter from the grain, and the cleaned grain is picked up continuously by a series of scoops and ejected forcibly from the cleaner.

As has been described, there is a sump disposed beneath the perforated cylinder, in which a continuously rotating auger is disposed and which operates to carry away the undesired matter expelled from the cylinder.

What I claim is:

1. A grain cleaning device comprising a stationary perforated cylinder, a shaft mounted within the cylinder and extending longitudinally thereof, a rotatable bladed member mounted on said shaft for agitating the grain during its movement through the cylinder in such a manner that extraneous matter is expelled from the grain through the perforated cylinder, a grain inlet-opening at one end of the cylinder, and a separate feed member on said shaft adjacent the opening and in the path of the incoming grain shaped to deflect and propel the grain directly into the path of said bladed member, the

said members being spaced substantially from the walls of the cylinder.

2. A grain cleaning device comprising a stationary perforated cylinder, a shaft mounted within the cylinder and extending longitudinally thereof, a rotatable bladed member mounted on said shaft for agitating the grain during its movement through the cylinder in such a manner that extraneous matter is expelled from the grain through the perforated cylinder, a grain inlet-opening at one end of the cylinder, a separate feed member on said shaft adjacent the opening and in the path of the incoming grain shaped to deflect and propel the grain directly into the path of said bladed member, the said members being spaced substantially from the walls of the cylinder, and scoop members at the opposite end of the cylinder for expelling the cleaned grain from the device.

3. A grain cleaning device comprising a stationary cylindrical screen member, a shaft mounted within said screen member and extending longitudinally thereof, a plurality of blades secured to said shaft in such a manner as to agitate the grain against the inner surface of the screen during the continuous movement of the grain therethrough, thus expelling the extraneous matter from the grain, a grain inlet-opening at one end of the screen member, a member having the shape of a portion of an auger and substantially one turn in length, mounted on said shaft adjacent the opening and in the path of the incoming grain operable to deflect and propel the incoming grain directly into the path of said blades, and a series of scoop members attached to the shaft at the opposite end of the cylinder for expelling the cleaned grain from the cleaner.

In testimony whereof I have hereunto affixed my signature.

ARTHUR J. HARTLEY.
